UNITED STATES PATENT OFFICE.

ROBERT W. PAIN, OF NEW YORK, N. Y., ASSIGNOR TO THE AEOLIAN COMPANY, OF SAME PLACE.

PEDAL ATTACHMENT FOR AUTOMATIC PLAYING DEVICES.

SPECIFICATION forming part of Letters Patent No. 630,557, dated August 8, 1899.

Application filed February 4, 1899. Serial No. 704,505. (No model.)

To all whom it may concern:

Be it known that I, ROBERT W. PAIN, a citizen of the United States, residing in the city of New York, borough of Manhattan, county 5 and State of New York, have invented certain new and useful Improvements in the Pedal Attachments for Automatic Playing Devices, of which the following is a specification.

My improvement relates to the pedal attachment of automatic playing devices—such, for example, as the "pianola."

I will describe a pedal attachment embodying my improvement and then point out the novel features in the claims.

15 In the accompanying drawings, Figure 1 is a side elevation of a portion of a piano-casing, which is partly in vertical section, and of an automatic playing device provided with a pedal attachment. Fig. 2 is a detail top view, 20 on an enlarged scale, of a portion of the pedal attachment. Fig. 3 is an elevational view, on an enlarged scale, of a pedal attachment embodying my invention. Fig. 4 is a detail elevational view, on an enlarged scale, of a portion of the pedal attachment.

Similar letters of reference refer to corresponding parts throughout the figures.

A represents a portion of a piano, a one of the pedals thereof, and B an automatic playing device—for example, a pianola—having a pedal attachment. This attachment, as is usual in this class of devices, is operated by a lever (not shown) within reach of an operator. This lever operates a shaft b, carrying 30 an arm b', which gives longitudinal movement to a vertical rod or shaft b², carrying the pedal. A guide b³, carried by the casing b⁴ of the pianola, is provided for the end of the shaft b².

C represents the pedal, having a collar c, 40 which is loose upon the shaft b². The collar c of the pedal is normally held against a collar c' by means of a spring c³. The collar c' is adjustable on the shaft b² by means of a set-screw c², and the adjustment of this collar permits of the adjustment of the pedal according to the height of the piano-pedal a.

c⁴ represents a flange or rim on the collar c', and c⁵ a recess or opening in said flange, in which a pin c⁶ on the collar c fits. The purpose of this arrangement is to prevent rotary movement of the pedal when in operative position. When the pedal is to be moved out of operative position, it is moved vertically against the action of the spring and rotated

on the shaft until it is in a position similar to that shown by dotted lines in Fig. 2. If desired, a second recess or opening may be provided in the flange c⁴, with which the pin may be engaged when the pedal is out of operative position.

c⁷ represents an adjustable collar on the shaft b² for limiting the vertical movement of the pedal when it is to be moved out of engagement with the flange or rim c⁴.

What I claim as my invention is—

1. The combination of a longitudinally-movable rod or shaft, an adjustable collar on said shaft, a pedal carried by said shaft and adapted to be moved vertically thereon independently thereof, and means for holding said 70 pedal in engagement with said collar.

2. The combination of a longitudinally-movable rod or shaft, an adjustable collar on said shaft, a pedal carried by said shaft so as to have vertical and rotary movement thereon, and a spring for holding said pedal in engagement with said collar. 75

3. The combination of a longitudinally-movable rod or shaft, an adjustable collar on said shaft, a rim or flange on said collar provided with an opening or recess, a pedal carried by said shaft so as to have vertical and rotary movement thereon, a pin on said pedal adapted to fit in said recess or opening, and a spring for holding said pin in said recess, 80 substantially as described. 85

4. The combination of a longitudinally-movable rod or shaft, a collar on said shaft, a pedal carried by said shaft, so as to have vertical and rotary movement thereon and 90 adapted to be locked with said collar, and means for limiting the vertical movement of said pedal on the rod or shaft.

5. The combination of a longitudinally-movable rod or shaft, a pedal carried by said 95 shaft and adapted to have vertical and rotary movement independently of the shaft, a collar carried by said shaft with which the pedal engages to prevent its rotary movement, and a second collar carried by said shaft for limiting the vertical movement of the pedal. 100

In testimony whereof I have signed my name to this specification in the presence of two subscribing witnesses.

ROBERT W. PAIN.
